US00D930300S

(12) **United States Design Patent** (10) Patent No.: **US D930,300 S**
Lee et al. (45) Date of Patent: ** Sep. 7, 2021

(54) **ROBOT VACUUM CLEANER**

(71) Applicant: **SAMSUNG ELECTRONICS CO., LTD.**, Suwon-si (KR)
(72) Inventors: **Hwan-Dong Lee**, Suwon-si (KR); **Sang-Hoon Yoon**, Suwon-si (KR); **Jin-Sun Park**, Suwon-si (KR); **Jae-Ho Jang**, Suwon-si (KR); **Hyun-Woo Yoon**, Suwon-si (KR)

(73) Assignee: **SAMSUNG ELECTRONICS CO., LTD.**, Gyeonggi-Do (KR)

(**) Term: **15 Years**

(21) Appl. No.: **29/735,888**

(22) Filed: **May 26, 2020**

(30) **Foreign Application Priority Data**

Nov. 28, 2019 (KR) 30-2019-0057452

(57) **CLAIM**

The ornamental design for a robot vacuum cleaner, as shown and described.

DESCRIPTION

FIG. 1 is a front perspective view of a robot vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view of a robot vacuum cleaner shown in an alternate position.

The broken lines illustrating portions of the robot vacuum cleaner form no part of the claimed design.

1 Claim, 8 Drawing Sheets
